UNITED STATES PATENT OFFICE.

PAUL GSCHWEND, OF CANTON, OHIO.

DESIGN FOR A TERRET.

SPECIFICATION forming part of Design No. 19,661, dated February 18, 1890.

Application filed January 13, 1890. Serial No. 336,847. Term of patent 14 years.

To all whom it may concern:

Be it known that I, PAUL GSCHWEND, a citizen of the United States, residing at Canton, in the county of Stark and State of Ohio, have invented a new and original Design for Terrets, of which the following is a specification.

The invention relates to a new and original design for terrets for harness-saddles.

10 In the drawings, Figure 1 is a perspective view of a terret showing my design. Fig. 2 is a side elevation of the same, and Fig. 3 is a vertical transverse sectional view.

15 The leading feature of my design is the rectangular or oblong loop having its inner faces slightly convex.

20 Referring to the drawings, A designates a rectangular loop, which has a horizontal oblong opening a, and is provided with a stem B, depending from the lower piece or bottom

a' of the loop A. The sides a', a², a³, and a⁴ have their inner adjacent faces slightly bulging or convexed, as shown in the drawings. The stem B is provided a short distance below the loop A with an annular flange b. 25

Having thus described my invention, I claim—

A design for terrets herein shown and described, the same consisting of the rectangular loop having the inner faces of its sides 30 convex and the stem having the annular flange, as set forth.

In testimony that I claim the foregoing as my own I have hereto affixed my signature in presence of two witnesses.

PAUL GSCHWEND.
